UNITED STATES PATENT OFFICE.

FRANK SOHN, OF CHICAGO, AND LOUIS G. MARMION, OF VILLA PARK, ILLINOIS, AS-SIGNORS TO THE VITROLITE COMPANY, A CORPORATION OF WEST VIRGINIA.

DESIGN FOR A DECORATIVE TABLE TOP.

Application filed August 17, 1927. Serial No. 23,130. Term of patent 7 years.

To all whom it may concern:

Be it known that we, FRANK SOHN and LOUIS G. MARMION, respectively, citizens of the United States and of the French Republic, respectively, residing at Chicago and Villa Park, in the county of Cook and State of Illinois, have invented a new, original, and ornamental Design for a Decorative Table Top, of which the following is a specification, reference being had to the accompanying drawing, forming part thereof.

The figure is a plan view of a decorative table top showing our new design; there being shown only one-half of the table top whose other half, the boundaries of which are indicated by the broken lines, is a repetition of that shown, the area between the two ends being a continuation of the detailed illustration.

We claim:

The ornamental design for a decorative table top, as shown and described.

FRANK SOHN.
